US00D892026S

(12) **United States Design Patent** (10) **Patent No.:** **US D892,026 S**
Zajac et al. (45) **Date of Patent:** **** Aug. 4, 2020**

(54) **AUTOCYCLE STORAGE POD**

(71) Applicants: **Christopher Zajac**, South Windsor, CT (US); **Marlon Fuller**, Winter Garden, FL (US)

(72) Inventors: **Christopher Zajac**, South Windsor, CT (US); **Marlon Fuller**, Winter Garden, FL (US)

(**) Term: **15 Years**

(21) Appl. No.: **29/669,515**

(22) Filed: **Nov. 8, 2018**

(51) LOC (12) Cl. **12-16**

(52) U.S. Cl.

USPC **D12/402**

(58) **Field of Classification Search**

USPC D12/400–403, 409, 410, 415, 114, 115; D25/16, 18; D6/663

CPC B62J 19/00; B62J 23/00

See application file for complete search history.
